UNITED STATES PATENT OFFICE.

ARLINGTON N. SANDT, OF RED WING, MINNESOTA.

PROCESS OF LETTERING.

1,403,449.

Specification of Letters Patent. Patented Jan. 10, 1922.

Application filed April 30, 1921. Serial No. 465,721.

To all whom it may concern:

Be it known that I, ARLINGTON N. SANDT, a citizen of the United States, and a resident of Red Wing, in the county of Goodhue and State of Minnesota, have invented a new and Improved Process of Lettering, of which the following is a full, clear, and exact description.

This invention relates to improvements in process of lettering, an object of the invention being to so letter a curved or receding surface that the word or words formed by the letters will have the same appearance as if the surface were a flat one.

15 A further object is to provide an improved process of lettering which has particularly to do with the labeling of cans, bottles, or other containers having cylindrical, angular, or other receding surfaces whereby the printing on the labels can be read and displayed with the same clearness and effect as if the surface were flat.

20 Cans, bottles, containers, etc., have heretofore been provided with labels printed with letters of the same size or uniform size, so that the letters on the receding portions of the surface appear smaller and are difficult to read, and it is the purpose of my invention to so proportion the letters that they 30 will appear of a uniform size when the article is in elevation, so that the labels can be prominently displayed.

With these and other objects in view the invention consists in certain novel arrangement of letters and process of forming the same, as will more fully hereinafter appear.

In the accompanying drawings—

Figure 1 is a view in elevation illustrating a fragment of the can containing a label or lettering in accordance with my improved process.

Figure 2 is a view in section through the can showing by dot and dash lines the position and proportions of the letters on the can shown in Figure 1.

Figure 3 is a plan view of the label used on the can shown in Figures 1 and 2.

1 represents an ordinary cylindrical can 50 and 2 a label pasted thereon containing letters arranged in accordance with my improved process. It will be noted particularly by reference to Figure 3 that the end letters 3 are preferably wider than the intermediate 55 letters, all the letters having the same height,

so that when the label is secured to the curved surface of the can and the can placed upon the shelf so that it is viewed in elevation, all of the letters will appear of the same general width as shown in Figure 1, so that 60 the appearance of the lettering is as if the word were upon a flat surface and not upon a curved or receding surface.

The relative proportions of the widths of these letters are to be varied in accordance 65 with the diameter of the can or rather the receding surfaces on which the letters are to be located, and it is obvious that the invention applies not only to a cylindrical container of curved cross-section, but to any form 70 of container either of glass, metal, or other material, either curved or angular in cross-section where there are receding surfaces upon which letters are to be formed to indicate the contents, or other printed matter 75 desired on the container, and it is also to be understood that I may form the letters directly on the can either by hand painting or by any other means and dispense with an attached label, and, in fact, my invention 80 is broadly to the idea of a process of lettering whereby a word or words are printed upon a surface in which a portion thereof is receding so that the word can be read as if printed upon a flat surface, and to accomplish this I proportion the letters on 85 the receding surface in such a way as to render such a result possible, and I desire to cover broadly this idea rather than any particular means for carrying it out. 90

Various slight changes might be made in the general form and arrangement of the parts described without departing from the invention, and hence I do not wish to limit myself to the precise details set forth, but 95 consider myself at liberty to make such changes and alterations as fairly fall within the spirit and scope of the appended claims.

I claim:

1. The hereindescribed process of lettering consisting in proportioning the width of letters whereby the letters when on a receding surface will have the appearance of uniform width. 100

2. The hereindescribed process of lettering consisting in forming letters on a receding surface, the letters farthest removed from the forward plane of the surface being appreciably wider than the other letters, whereby the letters taken together have the 110

appearance of being printed upon a flat surface.

3. The herein-described process of labeling containers having receding surfaces, comprising a series of letters in horizontal alignment, the end letters being of appreciably greater width than the intermediate letters.

4. The herein-described process of labeling cans consisting in providing letters on the can, the intermediate letters being appreciably narrower than the end letters, whereby the letters in assemblage appear as being printed upon a flat surface.

ARLINGTON N. SANDT.
